at the

UNITED STATES PATENT OFFICE.

JOHN B. HOLMER, OF CHICAGO, ILLINOIS.

CIGAR-HOLDER.

SPECIFICATION forming part of Letters Patent No. 276,042, dated April 17, 1883.

Application filed January 17, 1883. (No model.)

To all whom it may concern:

Be it known that I, JOHN B. HOLMER, of Chicago, county of Cook, and State of Illinois, have invented a new and useful Improvement 5 in a Cigar-Holder, of which the following is a full, clear, and exact description, that will enable others to make and use the same, reference being had to the accompanying drawings, and to letters of reference marked thereon, 10 forming a part of this specification.

This invention relates to improvements in cigar-holders; and it consists of certain novel features in the construction and arrangement of the parts, as will be hereinafter more fully 15 set forth in detail.

Figure 1 is a side elevation of a device embodying my improved features; Fig. 2, a longitudinal section, and Fig. 3 a detached detail of construction.

Referring to the drawings, A A' represent 20 the two parts composing the tubular stem, which have a threaded separable connection at a, which conveniently permits of these parts being disconnected that they may be more easily cleaned, or for the purpose of securing 25 the device in a more compact space. The lower curved end of the part A is provided with the bulb B, which receives the deposit of nicotine and the moisture entering the stem during the

process of smoking. This bulb has a screw- 30 threaded connection, so that it may be readily removed and the collected contents discharged. This part of the stem A is also provided with the sheath a' and the threaded socket projection a². This socket is adapted to receive the lower correspondingly-threaded end of the tubular conical-shaped impaling-point C. This 35 point is adapted to pierce the cigar B', for the purpose of retaining the same in place relative to the stem, and is provided with a number of holes, b, through which the smoke passes into the stem. These holes are set at alternate points, so as not to weaken this part of the structure, as would be the case were the perforations opposite each other or in the same 40 plane. When the holder is not required for use, the impaling-point C may be disengaged from the socket a² and inserted in the sheath a', as indicated by the dotted lines in Fig. 2

of the drawings. By this arrangement the 50 device may be more compactly folded when placed in a suitable case, or carried loosely in the pocket without any inconvenience from the sharp impaling-point C.

The part A' of the stem is provided with the 55 adjustable ring D, having the curved arms pivoted thereto, which are adapted to inclose and support that part of the cigar back of the point C. The curved arms d d', by reason of the pivot-joint d², are adapted to fold parallel 60 with the stem of the holder. The ring D may be moved up nearer to or farther away from the point C, according to the length of the cigar, and properly support the same until it is 65 entirely consumed.

E represents the mouth-piece, which is detachably connected to the part A' of the stem.

By this arrangement the smoke is cooled in 70 passing through the stem, and the moisture from the mouth cannot come in contact with the cigar. If only a portion of the cigar is consumed at one time, the remaining part may be laid aside for future use, as that part of the cigar back of the impaling-point is not injured or spoiled by the nicotine and smoke, for the 75 reason that the smoke does not pass through the whole length of the cigar, as is ordinarily the case.

Having thus described my invention, what I claim, and desire to secure by Letters Patent, 80 is—

1. In a cigar-holder, the combination, with the stem part A, provided with the threaded socket a², of the detachable tubular point C and the sheath a', substantially as and for the 85 purpose set forth.

2. The combination, with the stem of a cigar-holder, consisting of the two separable parts A A', of the adjustable ring D, provided with the supporting-arms d d', adapted to be folded 90 parallel with the stem, the tubular point C, provided with the series of perforations b, the sheath a', and the bulb B, all combined and arranged substantially as set forth.

JOHN B. HOLMER.
